FRANK C. WHITE, OF MERIDEN, CONNECTICUT, ASSIGNOR TO THE WILCOX & WHITE COMPANY, OF MERIDEN, CONNECTICUT, A CORPORATION OF CONNECTICUT.

PNEUMATIC PLAYER MECHANISM.

1,168,691.

Specification of Letters Patent.

Patented Jan. 18, 1916.

Application filed May 15, 1915. Serial No. 28,250.

To all whom it may concern:

Be it known that I, FRANK C. WHITE, a citizen of the United States of America, residing at Meriden, New Haven county, Connecticut, have invented a new and useful Pneumatic Player Mechanism, of which the following is a specification.

My invention relates to pneumatic music playing instruments, and particularly to regulating and controlling means whereby the tension of air in the action chest may be varied at will whenever it is desired to vary the degree of force with which the notes are to be struck whether the same be solo notes or accompaniment notes.

The invention in its preferred form is automatic in action.

In the accompanying drawing: I have shown my invention by means of a view mainly diagrammatic in character in which certain parts are shown in elevation and others in section.

I have shown the invention as applied to a player mechanism in which the action is divided, in this instance, into two sections, although the number of sections is immaterial in the broadest aspect of the invention.

1 represents conventionally a suitable exhauster preferably power-driven.

2 is a duct leading therefrom to the interior of a casing 3.

4 is a valved port in one wall of the casing which is controlled by a throttle valve 5 moved by a governor regulator pneumatic 6.

7 is a spring for distending the regulator bellows 6.

8 is a duct leading from the interior of the regulator pneumatic 6 to the interior of the casing 9.

10 is a valved passage or port in one wall of the casing 9.

11 is a throttle valve arranged to control the port 10, the said valve being movable by a second governor regulator pneumatic 12.

13 is a spring arranged to distend the regulator pneumatic 12.

14 is a port leading from the regulator pneumatic 12 to the section or chamber 15 of the action chest.

50 It will now be seen that the regulators 6 and 12 are arranged in series between the exhauster 1 and the action chest section 15, the purposes and advantages of which will later be described.

16 represents a tracker having the usual 55 note perforations or ducts 17 therein.

18 is a duct therein the function of which is to select solo or melody notes so that when the solo notes or perforations in the music roll (not shown) register with the perforations 17, such notes may be struck with a relatively increased vigor so as to sound out above the accompaniment notes. The duct 18 leads to a normally collapsed pouch pneumatic 19 which is capable, when distended, 60 of opening a valve 20 which normally closes a shunt passage from the interior of casing 9 to the interior of the regulator pneumatic 12.

21 is a duct in the tracker leading to a 70 normally collapsed pouch pneumatic 22 capable of opening a valve 23 which normally closes a shunt passage from the interior of casing 3 to the interior of the regulator pneumatic 6.

75 24 is a duct in the tracker leading to a normally collapsed pouch pneumatic 25 capable of opening a valve 26 which normally closes another shunt passage from the interior of chamber 9 to the interior of the 80 regulator pneumatic 12. This last mentioned duct, pouch pneumatic and shunt valve may be duplicated, and in the drawings I have shown three sets in all, the duplicated sets being indicated at 24^a, 25^a and 26^a, 85 24^b, 25^b and 26^b respectively.

27 is a duct in the tracker leading to a normally closed pouch pneumatic 28 capable of opening a valve 29 which normally closes a shunt passage from the interior of casing 3 90 to the interior of the regulator pneumatic 6. This duct, pouch pneumatic and shunt valve, may likewise be duplicated as shown. In this instance, four sets are shown, the ducts being respectively indicated at 27, 27^a, 27^b 95 and 27^c, the pouch pneumatics at 28, 28^a, 28^b and 28^c, the shunt valves at 29, 29^a, 29^b and 29^c.

30 is a casing corresponding to the 100 casing 9.

31 is a governor regulator pneumatic corresponding to the governor regulator pneumatic 12.

32 is a spring corresponding to the 105 spring 13.

33 is a passage or duct corresponding to the duct 14.

The pneumatic regulator 31 and its asso-

ciated parts are intended to control the tension of air within the chamber 34 of the action chest, in the same manner as the regulator pneumatic 12 controls the tension in the section 15 thereof. The interior of the regulator pneumatic 31 may have a throttle and shunt valves corresponding to the valves within the regulator pneumatic 12, and the valve therein corresponding to shunt valve 20 is controlled from a tracker duct 35 whereby when solo notes are to occur in the bass section, the duct 35 will be opened so as to function in the base section in the same manner as the valve 20 will function in the treble section. The tracker ducts 24-24^a and 24^b may have branches indicated at 24^c, 24^d and 24^e which lead to valves in the regulator pneumatic 31 corresponding to valves 26-26^a and 26^b in the regulator pneumatic 12.

Having now described the various parts of the apparatus, I will now proceed to describe the operation. It will be understood at the outset that the striker pneumatics, or action pneumatics (not shown) are associated with the action chest 34-15, and that the degree of force with which said striker pneumatics operate is determined by the degree of air tension within the action chest at the moment said striker pneumatic acts. Since the particular form of the striker pneumatic is well understood and its connection with the other parts of the instrument is also well understood, it is unnecessary to either show or describe the same herein, particularly as no novelty is ascribed thereto.

I will first describe the course of air from the section 15 of the action chest to the exhauster, and what normally occurs, and what may be caused to occur automatically. Air from the action chest 15 passes through branch 14 through the regulator pneumatic 12 and valved passage 10 to and through main duct 8 into the regulator pneumatic 6; thence through the valved passage 4 and thence to the exhauster 1 through duct 2. The regulators 6 and 12 are preferably adjusted so that they will normally control the air tension at different degrees of pressure. For example, the spring 13 is so adjusted that the air tension in the action chest section 15 will be controlled or maintained normally at its lowest point, so as to secure for example "pianissimo" effect. The spring 7 for the regulator pneumatic 6 is so adjusted that (were it not for the regulator 12), it would regulate and normally maintain in the action chest section 15, a somewhat higher degree of air tension to secure, for example, the "piano" effect. By this setting of the regulators, it is obvious that if the regulator 12 is in effect momentarily cut out, the air tension in the chest 15 would be for such moment or period maintained at

the established tension of the regulator 6. Now, assuming it is desired to strike a solo note in the treble section, the duct 18 is uncovered thus opening valve 20 so as to put the action chest section 15 in direct communication with the regulator 6, whereby any note then struck will be sounded at an increased tension, for example, at "piano" tension. Thus, by momentarily opening valve 20, the solo or melody notes may be caused to sound with one degree more vigor than such notes would be sounded with if the valve 20 were closed. If a still higher degree of vigor is desired, the duct 27 may be opened simultaneously with the duct 18, thus not only opening valve 20 in the regulator 12, but also valve 29 in the regulator 6. The opening of the latter valve steps up one degree more the tension in the regulator 6, and, hence, in the action section 15. The solo note may be struck with still more vigor by simultaneously opening ducts 18, 27 and 27^a, and yet still more by opening the ducts aforesaid and duct 27^b and 27^c.

Since the ducts 27 to 27^c control the valves 29 to 29^c in the regulator 6, and since this regulator is in common to the regulators 12 and 31, it follows that whenever a solo note is to occur in the bass section 34 of the action, the solo note is selected by the duct 35 instead of the duct 18, and the same valves 29 to 29^c may be opened singly or in groups to determine the exact degree of force with which the solo note is to be struck. Should a so-called "crash" effect be desired at any time in one section, say section 15, the ducts 18 and 21 would be simultaneously flushed to open the preferably larger shunt valves 20 and 23. If the "crash" effect were desired in the bass, the tracker ducts 35 and 21 would be simultaneously opened. If the "crash" effect were desired in the entire action chest, the tracker ducts 18, 35 and 21 would be simultaneously opened.

I have not only provided means for sounding solo notes with the desired added vigor, but I have also employed means for automatically increasing the degree of force with which the accompaniment notes may be struck and to this end I have provided shunt valves 26, 26^a and 26^b in the regulator pneumatic 12, and corresponding valves in the regulator pneumatic 31, which valves may be opened by uncovering the tracker ducts 24, 24^a and 24^b. It follows that the uncovering of the duct 24 for example will let air pass somewhat more freely through both regulator pneumatics 12 and 31, and hence a corresponding increase in tension will occur in the action chest section 15 and 34, which may be still further increased by opening the valves 24^a and 24^b. By this comparatively simple arrangement, perforated note sheets may be readily produced with perforations therein so arranged as to

automatically control the degree of force with which any or all of the notes shall be struck, and it is important that for the purpose of selecting solo notes, the selector perforations for notes in the treble section are in one line, and the same is true of the selector perforations for notes in the bass section, the other expression controlling perforations being added whenever required.

10 It will be understood of course that my new system of control may be availed of by the use of apparatus which may be substantially modified from that shown and described herein, without departing from the 15 spirit and scope of my invention.

What I claim is:

1. In a pneumatic player mechanism, an air tension regulating system comprising a chamber from which air is to be exhausted, 20 an exhauster, a wind-way leading from the former to the latter, and two governor regulator pneumatics arranged in series in said wind-way and means for controlling one of said regulator pneumatics to vary its tension 25 regulating effect.

2. In a pneumatic player mechanism, an air tension regulating system comprising a chamber from which air is to be exhausted, an exhauster, a wind-way leading from the former to the latter, and two governor regulator pneumatics arranged in series in said wind-way, a tracker board, a normally closed shunt passage for one of said regulators with means controllable from the tracker 30 for opening said shunt passage.

3. In a pneumatic player mechanism, an air tension regulating system comprising a chamber from which air is to be exhausted, an exhauster, a wind-way leading from the former to the latter, and two governor regulator pneumatics arranged in series in said wind-way, one of said regulator pneumatics being arranged to offer normally greater resistance to the passage of air than the other 40 regulator, the regulator offering the greater resistance being nearer to the chamber from which air is to be exhausted.

4. In a pneumatic player mechanism, an air tension regulating system comprising a chamber from which air is to be exhausted, an exhauster, a wind-way leading from the former to the latter, two governor regulator pneumatics arranged in series in said wind-way and normally operating to partially 50 throttle the passage of air from said chamber to said exhauster, and a normally closed shunt passage to modify the action of one of the regulators, with means for opening and closing said shunt passage at will.

5. In a pneumatic player mechanism, an air tension regulating system comprising a chamber from which air is to be exhausted, an exhauster, a wind-way leading from the former to the latter, two governor regulator pneumatics arranged in series in said wind- 60

way and normally operating to partially throttle the passage of air from said chamber to said exhauster, and a normally closed shunt passage to modify the action of one of the regulators, with means for opening 70 and closing said shunt passage at will, said means comprising a pneumatic, a tracker board having a duct leading to the last mentioned pneumatic to control the same.

6. In a pneumatic player mechanism, an 75 air tension regulating system comprising the chamber from which air is to be exhausted, an exhauster, a wind-way leading from the former to the latter, two governor regulator pneumatics arranged in series in said wind-way, a shunt passage for each of said regulators, and means for opening and closing said shunt passages independently or simultaneously.

7. In a pneumatic player mechanism, an 85 air tension regulating system comprising the chamber from which air is to be exhausted, an exhauster, a wind-way leading from the former to the latter, two governor regulator pneumatics arranged in series in said wind-way, a shunt passage for each of said regulators, and means for opening and closing said shunt passages independently or simultaneously, the regulator nearest the chamber 90 to be exhausted being arranged to effect a different tension from the other regulator.

8. In a pneumatic player mechanism, an air tension regulating system comprising a chamber from which air is to be exhausted, an exhauster, a wind-way leading from the former to the latter, two governor regulator pneumatics arranged in series in said wind-way, each regulator including a throttle valve for the wind-way controlled as to its 100 position by the degree to which said regulator is collapsed.

9. In a pneumatic player mechanism, an air tension regulating system comprising a chamber from which air is to be exhausted, an exhauster, a wind-way leading from the former to the latter, two governor regulator pneumatics arranged in series in said wind-way, each regulator including a throttle valve for the wind-way controlled as to its 110 position by the degree to which said regulator is collapsed, the regulator nearest the chamber to be exhausted being arranged to offer greater resistance to the passage of air through the wind-way than the other regulator, a shunt passage for the wind-way adjacent to the regulator nearest said chamber, and means for opening and closing said shunt passage at will.

10. In a pneumatic player mechanism, an 125 air tension regulating system comprising a chamber from which air is to be exhausted, an exhauster, a wind-way leading from the former to the latter, two governor regulator pneumatics arranged in series in said wind-way, each regulator including a throttle 130

- valve for the wind-way controlled as to its position by the degree to which said regulator is collapsed, the regulator nearest the chamber to be exhausted being arranged to offer greater resistance to the passage of air through the wind-way than the other regulator, a shunt passage for the wind-way adjacent to the regulator nearest said chamber, and means for opening and closing said shunt passage at will, and a plurality of shunt passages for the regulator nearest the exhauster, with means for opening simultaneously the shunt passage in the first mentioned regulator and one or more of the shunt passages in the second mentioned regulator. 11. In a pneumatic player mechanism, an air tension regulating system comprising a chamber from which air is to be exhausted, an exhauster, a wind-way leading from the former to the latter, two governor regulator pneumatics arranged in series in said wind-way, each regulator including a throttle valve for the wind-way controlled as to its position by the degree to which said regulator is collapsed, the regulator nearest the chamber to be exhausted being arranged to offer greater resistance to the passage of air through the wind-way than the other regulator, a shunt passage for the wind-way adjacent to the regulator nearest said chamber, and means for opening and closing said shunt passage at will, and a plurality of shunt passages for the regulator nearest the exhauster, with means for opening simultaneously the shunt passage in the first mentioned regulator and one or more of the shunt passages in the second mentioned regulator, said means including pneumatics, a tracker board and ducts leading therefrom to said pneumatics to control the same. 12. In a pneumatic player mechanism, an air tension regulating system comprising a chamber from which air is to be exhausted, an exhauster, a wind-way leading from the former to the latter, two governor regulator pneumatics arranged in series in said wind-way, a movable tension governing valve in said wind-way for each of said regulators tending to partially throttle the passage of air from the chamber to the exhauster, a plurality of shunt passages for each of said regulators, with means for opening and closing any of said shunt passages at will. 13. In a pneumatic player mechanism, an air tension regulating system comprising a chamber from which air is to be exhausted, an exhauster, a wind-way leading from the former to the latter, two governor regulator pneumatics arranged in series in said wind-way, a movable tension governing valve in said wind-way for each of said regulators tending to partially throttle the passage of air from the chamber to the exhauster, a plurality of shunt passages for each of said regulators, with means for opening and closing any of said shunt passages at will. 14. In a pneumatic player mechanism, an air tension regulating system including a plurality of chambers from which air is to be exhausted, an exhauster, a main wind-way having branches connecting said exhauster with the chambers to be exhausted, an air tension governor regulator in each of said branches tending to partially throttle the passage of air therethrough, an air tension regulator in the main wind-way, also tending to throttle the passage of air therethrough, the last mentioned tension regulator being arranged in series with each of the two first mentioned regulators. 15. In a pneumatic player mechanism, an air tension regulating system including a plurality of chambers from which air is to be exhausted, an exhauster, a main wind-way having branches connecting said exhauster with the chambers to be exhausted, an air tension governor regulator in each of said branches tending to partially throttle the passage of air therethrough, an air tension regulator in the main wind-way also tending to throttle the passage of air therethrough, the last mentioned tension regulator being arranged in series with each of the two first mentioned regulators, the two first mentioned regulators being arranged to offer greater resistance to the passage of air through their respective branches than does the regulator in said main wind-way. 16. In a pneumatic player mechanism, an air tension regulating system including a plurality of chambers from which air is to be exhausted, an exhauster, a main wind-way having branches connecting said exhauster with the chambers to be exhausted, an air tension governor regulator in each of said branches tending to partially throttle the passage of air therethrough, an air tension regulator in the main wind-way also tending to throttle the passage of air therethrough, the last mentioned tension regulator being arranged in series with each of the two first mentioned regulators, the two first mentioned regulators being arranged to offer greater resistance to the passage of air through their respective branches than does the regulator in said main wind-way, a shunt passage for each of the regulators in said branches, and means for opening and closing each of said shunt passages. 17. In a pneumatic player mechanism, an air tension regulating system including a plurality of chambers from which air is to be exhausted, an exhauster, a main windway

- having branches connecting said exhauster with the chambers to be exhausted, an air tension governor regulator in each of said branches tending to partially throttle the 5 passage of air therethrough, an air tension regulator in the main wind-way also tending to throttle the passage of air therethrough, the last mentioned tension regulator being arranged in series with each of the two first 10 mentioned regulators, the two first mentioned regulators being arranged to offer greater resistance to the passage of air through their respective branches, than does the regulator in said main wind-way, a shunt passage for 15 each of the regulators in said branches, and means for opening and closing each of said shunt passages, a tracker board, said opening and closing means being controllable therefrom.
- 20 18. In a pneumatic player mechanism, an air tension regulating system comprising a plurality of chambers from which air is to be exhausted, an exhauster, a windway connecting said exhauster with said chambers 25 and including branches leading respectively to said chambers from a main passage, a governor regulator pneumatic for the main passage, and a governor regulator pneumatic in each of said branches, said regulators being 30 respectively arranged to partially throttle the passage of air from said chambers to said exhauster, a plurality of shunt passages for all of said regulators, with means for opening and closing said shunt passages at 35 will.
- 35 19. In a pneumatic player mechanism, an air tension regulating system comprising a plurality of chambers from which air is to be exhausted, an exhauster, a windway connecting said exhauster with said chambers and including branches leading respectively to said chambers from a main passage, a governor regulator pneumatic for the main passage, and a governor regulator pneumatic in each of said branches, said regulators being 40 respectively arranged to partially throttle the passage of air from said chambers to said exhauster, a plurality of shunt passages for all of said regulators, with means for opening and closing said shunt passages at 45 will, a tracker with means controlled therefrom for in turn controlling said shunt passages.
- 50 20. In a pneumatic player apparatus, a chamber from which air is to be exhausted, an exhauster therefor, a wind-way leading from the former to the latter, two pneumatically governed throttles therein, said throttles being arranged in series and each 55 arranged to resist the passage of air through said wind-way and normally offering substantially unvarying resistance, and a shunt passage around one of said throttles, with means for opening and closing said shunt 60 passage.
- 65 21. In a pneumatic player apparatus, a chamber from which air is to be exhausted, an exhauster therefor, a wind-way leading from the former to the latter, two pneumatically governed throttles therein, said throttles being arranged in series and each 70 arranged to resist the passage of air through said wind-way and normally offering substantially unvarying resistance, and a shunt passage around each of said throttles, with 75 means for opening and closing said shunt passages.
22. In a pneumatic player apparatus, a chamber from which air is to be exhausted, an exhauster therefor, a wind-way leading 80 from the former to the latter, two pneumatically governed throttles therein, said throttles being arranged in series and each arranged to resist the passage of air through said wind-way and normally offering substantially unvarying resistance, the throttle 85 nearest the chamber to be exhausted being arranged to offer somewhat more resistance than the other throttle, and a shunt passage around the throttle offering the greater resistance, with means for opening and closing said shunt passage.
23. In a pneumatic player apparatus, a chamber from which air is to be exhausted, an exhauster therefor, a wind-way leading 90 from the former to the latter, two pneumatically governed throttles therein, said throttles being arranged in series and each arranged to resist the passage of air through said wind-way and normally offering substantially unvarying resistance, the throttle 95 nearest the chamber to be exhausted being arranged to offer somewhat more resistance than the other throttle, and a shunt passage around each of said throttles, with means for opening and closing said shunt 100 passage.
24. In a pneumatic player apparatus, a chamber from which air is to be exhausted, an exhauster therefor, a wind-way leading from the former to the latter, two pneumatically governed throttles therein, said throttles being arranged in series and each 105 arranged to resist the passage of air through said wind-way and normally offering substantially unvarying resistance, the throttle nearest the chamber to be exhausted being arranged to offer somewhat more resistance than the other throttle, and a plurality of shunt passages around each of said throttles, with means for opening and closing said shunt 110 passage.
25. In a pneumatic player apparatus, two chambers from which air is to be exhausted, an exhauster therefor, a wind connection 115 between said chambers and said exhauster comprising a main wind-way having two branches connected respectively with said chambers, a pneumatically governed throttle in the main wind-way, a pneumatically governed throttle in each of said branches, all 120
- 125 130

- of said throttles being arranged to resist the passage of air and to normally offer substantially unvarying resistance thereto, the throttle in said main wind-way operating in series with each of the throttles in the branches; a plurality of shunt passages around each of said throttles, with means for opening and closing each of said shunt passages pneumatically, a tracker board, one duct therein arranged to control one of the shunt passages around one of the branch throttles, and having another duct therein arranged to control one shunt passage around the other branch throttle, and having another duct therein to simultaneously control a shunt passage around each of said branch throttles and having another duct therein arranged to control a shunt passage around the main throttle.
26. In a pneumatic player apparatus, two chambers from which air is to be exhausted, an exhauster therefor, a wind connection between said chambers and said exhauster comprising a main wind-way having two branches connected respectively with said chambers, a pneumatically governed throttle in the main wind-way, a pneumatically governed throttle in each of said branches, all of said throttles being arranged to resist the passage of air and to normally offer substantially unvarying resistance thereto, the throttle in said main wind-way operating in series with each of the branch throttles and arranged to normally offer somewhat less resistance to the passage of air than offered by said branch throttles, a plurality of shunt passages around each of said throttles, means for opening and closing each of said shunt passages pneumatically, a tracker board, one duct therein arranged to control one of the shunt passages around one of said branch throttles, and having another duct therein arranged to control one shunt passage around the other branch throttle, and having another duct therein arranged to simultaneously control a shunt passage around each of said branch throttles, and having a series of ducts therein arranged to control a series of shunt passages around the main throttle.
